WINDSHIELD FOR CARRIAGES OR THE LIKE

Mary E. Willard, El Paso County, Colo.
(1126 N. Nevada Ave., Colorado Springs, Colo.)

Filed Dec. 19, 1961, Ser. No. 67,962

Term of patent 3½ years

(Cl. D14—14)

Fig. 1

Fig. 3

The stroller shown in broken lines in FIGURE 1 is included for illustrative purposes only. The side not shown is a mirror image of the side shown.

I claim:

The ornamental design for a windshield for carriages or the like, as shown and described.
